Patented Oct. 29, 1918.

UNITED STATES PATENT OFFICE.

HENRY G. KURTZHALS, OF SHIPPENSVILLE, PENNSYLVANIA.

PIPE-TONGS.

1,283,217.

Specification of Letters Patent.

Patented Oct. 29, 1918.

Application filed March 15, 1916. Serial No. 84,439.

To all whom it may concern:

Be it known that I, HENRY G. KURTZHALS, a citizen of the United States, residing at Shippensburg, in the county of Clarion and State of Pennsylvania, have invented 5 certain new and useful Improvements in Pipe-Tongs, of which the following is a specification.

An object of my invention is to provide a 10 pair of tongs of the crossed handle type constructed and arranged in such a manner that the gripping jaw of one of the handles is made hook-shaped to overhang the remaining jaw and is mortised or cored out to receive any one of a plurality of liners or 15 bushings having various sized openings formed therein to accommodate the same to the different sizes of pipe with which the tongs may be used, the remaining handle being provided with a die or grip interchangeably mounted on the jaw thereof in such relation that as gripping force is exerted on the handle, this die or grip will engage with the pipe and will cause the same to be more 20 tightly held in the opening of the liner or bushing, while at the same time presenting a roughened surface to prevent turning of the pipe.

With the above and other objects in view, 25 my invention consists in certain novel features of construction and combinations of parts which will be hereinafter set forth in connection with the accompanying drawings and then more particularly pointed out in 30 the claim.

In the drawings:

Figure 1 is a view in side elevation of a 35 pair of tongs constructed after my invention.

Fig. 2 is a view in top elevation of the tongs disclosed in Fig. 1.

Fig. 3 is a longitudinal sectional view 40 through the main gripping jaw.

Fig. 4 is a view in elevation of one of 45 the liners or bushings.

Fig. 5 is a perspective view of one of the liners.

Fig. 6 is a fragmentary detail view of the 50 main gripping jaw looking into the same and with the liner removed.

Fig. 7 is a view similar to Fig. 3, showing the secondary gripping jaw.

Fig. 8 is a fragmentary detail view looking 55 toward the gripping jaw shown in Fig. 7 with the grip removed.

Fig. 9 is a view in perspective of one of the dies or grips.

Fig. 10 is a view in side elevation of one of the liners to be fitted to the main jaw.

The handles 1 and 2 are pivoted together 60 by means of the pin or rivet 3 and these handles are made of sufficient length that the proper fulcrum or leverage may be obtained.

The handle 1 is offset to one side as at 4 65 and is then shaped in a curved formation to provide the hook-shaped gripping jaw 5, which jaw is so shaped that the bill 6 is substantially in line with the main extent of the handle 1. The handle 2 is extended past the 70 bearing for the pin 3 to form the jaw 7 which is substantially in line with the main extent of the handle and this jaw is cut across or beveled as at 8 on its extreme outer end.

It is the intention that the pipe shall be 75 fitted in such a relation that the jaw 5 is disposed with the bill 6 thereof hooked around the same and that the handles 1 and 2 shall then be manipulated to bring the jaw 7 80 against the pipe, and it is therefore desirable that the inner face 9 of the jaw 5 be shaped to the arc of a circle of a slightly greater diameter than the largest size of pipe on which the tongs are intended to be 85 used. The jaw 7, on the beveled face 8 thereof is notched out to provide a recess 10, and a mortise opening 11 is formed into the metal of the jaw beyond this notched out opening at 10. A die or grip 12 is shaped 90 to be received in the notched opening 10 and is provided with a tongue 13 of tenon shape, to be received in the mortise 11, the outer face of the grip 12 being provided with the biting teeth 14. The jaw 7 95 and the tongue or tenon 13 have openings provided in alignment therethrough and a pin or rivet 15 is fitted through these aligned openings to hold the grip 14 secured within the notched out opening 10, and it will thus be seen that by removing this pin or rivet 15 the grip 12 may be removed from its operative position and may be reversed to reverse the biting teeth 14 or may be replaced with a new grip having the same form of biting 100 teeth or having a greater or lesser number of teeth of the same or a varied configuration.

The gripping face 9 of the jaw 5 is mortised out as at 16, and at the extreme end of the bill 6, a notched opening 17 is provided 110

in this face. The liners or bushings 18 are provided with the tongues or tenons 19 adapted to be received in the mortise 16 of the jaw 5, and these liners or bushings are 5 provided with the extensions 20 to be received over the extreme end of the bill 6 and to form a smooth joint at this point, the lug or rib 21 being provided adjacent the extension 20 to be received in the notched 10 out opening 17 of the jaw to hold the liners or bushings against side twisting movement or displacement from the proper operative relation. This rib 21 extends at an angle across the liner 23 between the outer side of 15 the liner and the under face of the extension or projecting end 20 for reinforcing this projecting end 20. The sides of the jaw 5 and the tongues 19 are provided with aligned openings and the pin or rivet 22 is fitted 20 through these aligned openings to secure the liners or bushings in the proper relation. The liners of which there may be any number, it being preferable that these liners be furnished with each pair of tongs in a set 25 comprising a separate liner for each individual size of pipe from the largest which will be taken by the tongs to the smallest size which the tong is adapted to operate upon, have the body portions thereof cut or shaped 30 out to provide the gripping opening 23, which is formed on the arc of a circle of slightly greater diameter than the pipe to be operated upon, similar to the formation of the gripping face 9, and thus when the 35 proper liner is fitted in place to operate upon the size of pipe being worked, the pipe will be embraced throughout substantially half or more of its circumference in this reasonably closely fitting liner or bushing, and as 40 the handles 1 and 2 are pressed together, the grip 12 will be brought to bear against the protruding side of the pipe, and consequently, a very efficient gripping action will be accomplished as the pipe is held in the 45 opening of the liner against rolling movement to shift from the engagement from the teeth 14 of the grip 12, and the turning movement exerted upon the handles of the tongs, in an inwardly swinging path in accordance with the disclosure in Fig. 1, will 50 cause these teeth to bite more deeply into the pipe and in consequence as the pressure exerted in the turning action is increased, the biting force of the teeth 14 will be correspondingly greater. While the jaw 7 will 55 come to a hard gripping bearing against the pipe, there is not any tendency of the parts to jam or to become wedged upon the pipe, by reason of the fact that the jaw 7 is beveled across as at 8, and the toothed face of 60 the grip 12 follows this same line of bevel. While I have herein shown and described the grip and the liners as being of specific form, held in the jaws by having the tongues thereof fitted in the mortises, and then pinned through, it will of course be apparent to those skilled in the art that changes might be resorted to in the fastening means, that the form and configuration of the grip and liners may be varied, and that a number of modifications and changes might be resorted to without departing from the spirit and scope of my invention, and hence I wish to be limited only to such points as may be set forth in the claim. 75

I claim:

As a new article of manufacture a pipe wrench comprising a pair of handles pivotally connected together, a jaw formed on each handle, one of said jaws provided with an arcuate gripping face, a liner fitting upon the gripping face of said last mentioned jaw, said last mentioned jaw provided with a mortise formed therein near the center thereof, said last mentioned jaw also provided with a second mortise near the outer end thereof, a tenon formed upon said liner and fitting in said first mentioned mortise, a projecting end extending at an angle from said liner and overhanging the end of said last mentioned jaw, a rib projecting at an angle across said liner between the outer side of said liner and the under face of said projecting end for reinforcing the same, and adapted to fit in said second mortise for 85 firmly holding the outer end of said liner against shifting movement. 90

In testimony whereof I affix my signature in presence of two witnesses.

HENRY G. KURTZHALS.

Witnesses:

R. EARL BESLEY,
JOSEPH SMITH.
